UNITED STATES PATENT OFFICE.

JOHN W. KISSELBURG, OF PURCELL, OKLAHOMA, ASSIGNOR OF ONE-HALF TO LAFAYETTE A. REEVES, OF PAULS VALLEY, OKLAHOMA.

BOLL-WEEVIL EXTERMINATOR.

Application filed October 26, 1923. Serial No. 670,928.

The present invention relates to a new and improved insect destroyer and more particularly to means to exterminate boll weevil that is, for destroying cotton bolls.

5 The main object of the invention is to provide a means to generate and dispense a poisonous smoke directly onto the cotton plant and which includes a hood or cover arranged above the smoke dispensing means 10 to insure thorough distribution of the smoke through the plant.

A further object of the invention is to provide a machine of the above type that can be used in connection with a cultivator 15 of any standard type.

Various other objects and advantages of the invention will become apparent during the continuance of the following description.

In the drawings:—

20 Figure 1 is a view in side elevation, showing my invention in its preferred embodiment.

Figure 2 is a view in top plan, showing one 25 of the compartment covers removed to disclose the interior construction thereof, the interior construction of the other compartment being shown in dotted line.

Figure 3 is a view in front elevation.

Figure 4 is a view in cross section taken 30 on line 4—4 of Figure 3.

Figure 5 is a view in end elevation of a cover that is arranged over the smoke dispensing spout.

In describing the invention in detail, containers A and B which are connected by a 35 bottom member 10, (Fig. 4) comprise the body portion of the machine. The containers A and B are divided by a partition 11 to form a dispensing compartment 12 to the rear, and a heat compartment 13 toward 40 the front. As will be observed upon reference to Figure 4 the compartment 13 is provided with a grate 14 spaced from the bottom thereof, opening 15 through which 45 access may be had below the grate; an opening 16 just above the grate, which may be closed, when desired, by the door 17 and the upper end of the compartment is divided off into a containing space 18 through the 50 medium of a partial partition 19. The partition 19 does not extend entirely across the compartment 13 but leaves an opening 20 through which the contents of the container 18 can be fed downwardly. The opening 20

however, is normally closed by a slide 21 55 whose movement is controlled by an arm 22 that projects outwardly of the container 18 through an opening 23 and connects to one end of a rock bar 24. Upon reference to Figure 2 it will be observed that the rock 60 bars 24 are pivotally mounted on brackets 25, as at 26, and that the other end connects with the front end of a handle member 27 that extends rearwardly through an eye 28 whereby it may be conveniently operated by 65 the operator of the machine as will be hereinafter fully described.

A fire is adapted to be made on the grate 14 and the container 18 is adapted to contain a poisonous powder which can be fed onto 70 the fire through the medium of slide 21, as is obvious.

It will also be noted that the partitions 11 are provided with openings 29 whereby the smoke generating in compartment 13 may 75 pass into compartment 12.

The body portion of the machine, consisting of members A and B is mounted on an axle 30, as at 31, the said axle carrying wheels 32, of any suitable or desired structure. The 80 hub of wheels 32, carry sprockets 33 for the purpose that will presently appear.

Within the compartments 12, I mount an axle 34 which carries a fan member 35 and a gear wheel 36. Externally of the compartment 12, is mounted a bracket 37 and another axle projects through the bracket, and the adjacent wall of the compartment into the respective compartment 12 as clearly shown in Figure 2. This axle is designated 90 by the numeral 37' and at its inner end carries a gear wheel 38 to mesh with gear wheel 36 on axle 34 and between the bracket and the outer wall of the container carries a small sprocket gear 39. Chains 40 operate 95 over sprocket wheels 33, carried by wheels 42 and the small sprocket gears 39 carried by axle 37'. Thus it will be observed that when the wheels 32 are rotated, chains 40 will cause rotation of sprocket gears 39 which will in turn rotate shaft 37' and the rotation of the shaft 37' will be imparted to the shaft 34 through the medium of co-meshing gears 36 and 38 thus rotating fan member 36. The compartment 12 is provided 100 with openings 41 at the lower rear ends, which openings lead into depending angular dispensing spouts 42 that are carried ex-

teriorly of the compartment 12, as at 43. Detachable pipe like nozzles 44 are associated with spouts 42 and project rearwardly and downwardly of the machine as is clearly shown in Figure 1.

The operator's seat 45 is carried upon a spring member 46 whose forward end is secured to the bottom member 10 of the machine, as at 47, so that the seat will assume 10 a position slightly in the rear of the body portion of the machine and about on the level of the top thereof.

Hinged covers 48 are provided for compartment 13 while removable covers 49 close 15 the upper ends of compartment 12.

From the foregoing, it will be observed that when there is a fire on the grate 14 and the poisonous powder from container 18 is fed into the fire a smoke will be generated 20 in compartment 13 which will pass through opening 29 in compartment 12. As the machine moves forward, the fan 35 will be rotated thus forcing the smoke out of compartment 12 through opening 41 into spout 25 42 and outwardly through nozzles 44. The nozzles 44 assume a position directly over or between the plants over which the machine travels so that the smoke emitted therefrom will circulate among the plants and destroy 30 the boll weevil or other insects which infect the latter.

In order to insure a more thorough distribution of the smoke mixture from nozzle 44 about the plants through which the machine travels, and at the same time to cause 35 the smoke to be held about the plants, a short time after it is emitted from the nozzle, I provide a cover like arrangement to be positioned over the nozzles 44. With this in 40 view, I provide a cover like structure which consists of side pieces 50, connected at their rear ends by a semicircular bracket 51 and intermediate thereof by a slightly larger semicircular bracket 52. The space between 45 brackets 51 and 52 is covered by a suitable covering 53 while a connecting rod 54 is employed to connect the upper ends of the bracket and form a reinforcement for the cover. At the rear end the material that 50 forms the cover proper is extended beyond bracket 51 to form a sheet or curtain 55 slit at spaced points, as at 56, to partially close the rear end of the cover, yet to permit the machine to pass over the cotton plants.

55 The front end of members 50 are connected as at 57, through a bracket 58 carried by the body portion of the machine. It is preferable that the members 50 be placed only slightly above the ground over which 60 the machine travels so that the cover 53 will form a hood over the cotton plants and thus insure a better distribution of the smoke to the end that boll weevil and other insects will be destroyed.

65 The sides of the vehicle may be provided

with aprons forming continuations of the side portions of hood 53, and these aprons depend from the outer sides of the members A and B and terminate a short distance above the ground. The aprons, as well as 70 the side portions of hood 53, are attached at their lower ends to the side members 50, the latter also having attached thereto the lower ends of the stays 51—52. The stay 52 has secured to its upper portion the lower end 75 of a link 63, the upper end thereof being attached to a rearwardly projecting arm forming part of a lever 60 pivoted as at 61 to a part of the vehicle and traveling upon a segment 62. The handle 64 of the lever 80 60 is in convenient reach of the driver occupying the seat 45, and suitable latch arrangement associated with the lever and segment maintains the lever in desired positions of adjustment. It is obvious from 85 this construction that the hood may be adjusted toward or away from the ground, to compensate for growing plants of various heights. By extending the aprons forwardly from the sides of the hood, an elongated 90 fume confining space is provided, the utility of which is apparent, as the fumes may be more intimately brought into contact with the plants in being liberated beneath the hood.

95 Suitable brake means and other appurtenant mechanism may be employed in placing the machine in actual practice, but inasmuch as it does not form subject matter of the present invention, it has not been described 100 or shown in detail.

Upon reference to Figure 1, it will be noted that I provide a tongue or other connecting member 59 that projects forwardly of the body portion of the machine for purposes that are obvious.

105 The powder to be used in container 18 is of a poisonous nature and is designed to generate a dense smoke with poison fumes when fed on the fire on the grate 14. The 110 powder, while generating poisonous fumes that will destroy insects such as boll weevil, the fumes will not be found harmful to the human system.

115 From the foregoing, it is believed that the advantages and novel features of my invention will be readily understood and therefore further detailed description is deemed unnecessary.

120 What is claimed is:—

In a device of the class described, a vehicle having a platform, a bracket depending from the forward end of said vehicle and having its ends out turned and disposed horizontally and relatively close to the ground, 125 side bars disposed beneath said vehicle and hingedly connected at their forward ends to said out turned portions of the bracket, a pair of yoke members arranged in inverted position in spaced relation beyond the rear 130

of said vehicle and having their lower ends secured to said side members, a rod connecting the upper portions of said yoke members together, a hood supported by said yoke members and rod, aprons depending from the sides of said vehicle and secured at their lower ends to said side bars, a lever

on said vehicle, a connection between said lever and one of said yokes, and fume producing apparatus on said vehicle to direct ¹⁰ fumes into the forward end of said hood.

In testimony whereof I affix my signature.

JOHN W. KISSELBURG.
